UNITED STATES PATENT OFFICE.

LE ROY A. CRUMLEY, OF NEW YORK, N. Y., ASSIGNOR TO ISRAEL J. TOMBACHER, OF NEW YORK, N. Y., AND HARRY M. FELTENSTEIN, OF CHICAGO, ILLINOIS, COPARTNERS, DOING BUSINESS AS M. EISENBERG & SON.

DESIGN FOR A BRACKET FOR LIGHTING FIXTURES OR SIMILAR ARTICLES.

Application filed February 24, 1923. Serial No. 5,251. Term of patent 3½ years.

To all whom it may concern:

Be it known that I, LE ROY A. CRUMLEY, a citizen of the United States, and a resident of New York, county of Bronx, and State of New York, have invented a new, original, and ornamental Design for a Bracket for Lighting Fixtures or Similar Articles, of which the following is a specification, reference being had to the accompanying drawing, forming a part hereof.

Figure 1, in the drawing, shows a side elevation of the bracket and Figure 2 shows a front elevation of the bracket with parts broken away.

I claim:

The ornamental design for a bracket for lighting fixtures or similar articles, substantially as shown.

LE ROY A. CRUMLEY.
